UNITED STATES PATENT OFFICE.

SAMUEL C. WARNER AND ROBERT B. WARNER, OF HOLYOKE, MASSACHUSETTS; SAID ROBERT B. WARNER ASSIGNOR TO SAID SAMUEL C. WARNER.

PAPER-FINISHING MACHINE.

No. 853,610.

Specification of Letters Patent.

Patented May 14, 1907.

Application filed July 17, 1906. Renewed April 20, 1907. Serial No. 369,405.

To all whom it may concern:

Be it known that we, SAMUEL C. WARNER and ROBERT B. WARNER, citizens of the United States, residing at Holyoke, in the county of Hampden and State of Massachusetts, have invented new and useful Improvements in Paper-Finishing Machines, of which the following is a specification.

This invention relates to machine for finishing the surface of paper, and aims to provide a machine of such class with means as hereinafter more specifically described for imparting to paper blanks a cloth or satin finish, and further, more particularly aims to set up a machine of such class for facilitating and expediting cloth or satin finishing of the surface of paper blanks, and, at the same time, subjecting the paper blanks to a duplex finishing operation by feeding the paper blanks to between a pair of endless belts traveling over two pairs of presser rolls which act upon the paper blanks through the belts.

The invention further aims to provide a paper finishing machine for the purpose set forth which shall be simple in its construction, strong, durable, efficient in its operation, easily adjustable, readily set up, and comparatively inexpensive to manufacture.

With the foregoing and other objects in view, the invention consists in the novel construction, combination, and arrangement of parts hereinafter more specifically described and illustrated in the accompanying drawings, which form a part of this specification, and wherein is shown the preferred embodiment of the invention, but it is to be understood that changes, variations, and modifications can be resorted to which come within the scope of the claims hereunto appended.

In describing the invention in detail, reference is had to the accompanying drawings, wherein like reference characters denote corresponding parts throughout the several views, and in which:

Figure 1 is a side elevation of a paper finishing machine in accordance with this invention, Fig. 2 is a front elevation, and Fig. 3 is a detail showing a portion of one of the surface finishing belts.

Referring to the drawings by reference characters, 4 denotes a base plate having at each end a vertically extending supporting frame, each of which is formed of a pair of uprights 5, 6 suitably spaced apart and con-

nected together at their top by the entablature 7. Each of the uprights 5, 6, has its lower end provided with a pair of laterally extending lugs 8, through which extend holdfast devices 9, the latter also extending through the base 4. The entablature 7 of each frame is connected to its respective uprights by the holdfast devices 10, which extend through the entablature and apertured lugs 11 formed on the uprights 5, 6. The holdfast devices 9, 10 are in the form of bolts 65 and nuts. One of the supporting frames is adjustable toward the other, and, to permit of such adjustment, the holdfast devices 9 for one of the supporting frames extend through suitable slots in the base 4, as indicated by the reference character 10.

Mounted in each of the supporting frames is a pair of vertically adjustable or sliding bearings 13 and a pair of lower stationary bearings 14. The pairs of bearings in each frame are positioned in alinement with each other and the pairs of bearings in one frame are positioned in alinement with the pairs of bearings in the other frame. The lower face of the sliding bearings 13 are cut away in a semi-circular manner, as at 15, and the upper face of the stationary bearings are constructed in a similar manner, as at 16. The bearings 13, 14 are adapted to respectively engage and support the presser rolls in a manner as hereinafter set forth.

The reference characters 21, 22, 23, and 24 denote a series of presser rolls, the roll 22 being arranged in vertical alinement with the roll 21, and the roll 24 being arranged in vertical alinement with the roll 23. The latter opposes the roll 21, and the roll 22 opposes the roll 24, and, by such arrangement, the rolls 21 and 23 constitute an upper pair of presser rolls, and the rolls 22, 24 constitute a lower pair of presser rolls. These rolls are constructed of a metallic material with a smooth periphery. The shafts for rolls 21, 23 are indicated by the reference character 25, and the said shafts are engaged in the two upper pairs of bearing brackets 13; and the shafts for the rolls 22, 24 are indicated by the reference character 26, and these shafts are journaled in the two pairs of lower bearing brackets 14. One of the shafts 25 extends from one of the supporting frames, as at 27, and carries a pulley 28 over which travels a belt 29, the latter also traveling

over a pulley 30 carried on the projecting end 31 of the shaft 32, which is journaled, as at 33, in one side of one of the uprights 6 of each of the supporting frames. One of the shafts 5 projects from one of the supporting frames, as at 34, and carries a drive pulley 35 connected by a belt 36 with a prime mover, not shown.

The rolls 21, 23 are connected together by 10 an endless belt 37. This belt is termed one of the surface finishing belts. The rolls 22, 24 are connected together by an endless belt 38, and this belt is termed the other of the surface finishing belts. Each of the belts 15 37, 38 is constructed of an inner and outer section 39, 40, respectively, Fig. 3. The belts may be constructed of any suitable material, but preferably formed of two sections, with the outer section of a textile fabric, such 20 as cotton or linen cloth, and the inner section of resilient material, by way of example, rubber. The said sections 39 and 40 are suitably connected together, and the section 39 of one belt opposes the section 39 of the other belt, 25 and between which is carried the paper to be finished. The sections 39 operate upon the paper under pressure while the belts 37, 38 are traveling, and the exerting of such pressure, in connection with the textile material 30 of which the sections 39 are constructed, gives to the paper a cloth or satin finish. The resilient section of each belt constitutes a yielding support for the material when the pressure of the rolls is had against the belts. 35 The rolls 21, 22 are arranged in close proximity to each other, and the same is true of the rolls 23, 24, so that, when the paper is fed to between the belts 37, 38 and passes between the presser rolls, the rolls will, what 40 may be termed, bite the paper. Owing to the employment of the two pairs of rolls, a duplex finishing operation is given to the paper. This will be evident, as, not only will the rolls 21, 22, owing to their arrangement 45 in close proximity to each other, exert pressure upon the belts between which the paper is fed, and thereby cause the imparting of a cloth or satin finish to the paper, but such action will also be had by the rolls 23, 24. 50 The feeding device for the paper is formed of two pairs of shafts, indicated by the reference characters 32, 41, 42, 43, and the shafts 32, 41 are arranged below the shafts 42, 43, and the shaft 41 is arranged above the plane 55 of the shaft 32, and the same is true of the shaft 43 with respect to the shaft 42. The shafts 32, 41, as well as the shafts 42, 43, are connected together by a series of what may 60 be termed ribbon belts 44, 45, the latter series traveling over the shafts 32, 41, and the former series traveling over the shafts 42, 43. By arranging the shafts 32, 41, 42, 43 in a manner as stated, the belts 44, 45 extend at 65 an inclination, and the paper is caused to travel upwardly toward the roll 21 and belt

37 and at an inclination with respect to the roll 22 and belt 38. The shafts 41, 42, and 43 are journaled in protuberances 46 extending from the uprights 6 of one of the supporting frames of each pair of supporting frames, 70 the said protuberances being arranged on each face of the uprights 6.

The belts 37, 38 are kept under tension through the medium of an upper and a lower stretcher roll 47, 48, the former bearing 75 against the belt 37, and the latter bearing against the belt 38. The stretcher roll 47 is journaled in a pair of vertically movable cross bars 49, which are adjustably connected, as at 50, to the uprights 5 of each pair of 80 supporting frames, and the roll 48 is journaled in a pair of vertically adjustable cross bars 51, which are adjustably connected, as at 52, to the lower end of the uprights 5 of each pair of supporting frames. If either of 85 the belts 37 or 38 should become slack, it will be evident that, by adjusting either the roll 47 or 48 toward a belt depending upon which belt has become slack, the said stretcher roll will cause its respective belt to assume a taut 90 position.

The machine is provided with a pair of belt wiper or dust rolls, which are positioned at the rear thereof and are indicated by the reference characters 53, 54, the roll 53 being 95 arranged near the top of the machine, and the roll 54 near the bottom of the machine. The roll 53 is carried by a shaft 55 which is journaled in an upright 6 of a supporting frame of each of the supporting frames, and is connected by a transmission belt 56 to the shaft 42. The roll 54 is carried by a shaft 57, which is journaled in an upright 6 of a supporting frame of each of the supporting frames, and said shaft 57 is connected by a 100 transmission belt 58 to the shaft 32.

At the rear of the machine a conveying device for the finished sheets is provided, and the said device consists of an upper and a lower pair of shafts, the upper pair being indicated by the reference characters 59, 60, and the lower pair being indicated by the reference characters 61, 62. The shaft 62 is arranged above the shaft 61, and the same is true of the shaft 60 with respect to the shaft 110 59. The upper pair of shafts 59, 60 are connected together by what may be termed ribbon belts 63, and the same is true of the shafts 61, 62. The belts for the shafts 61, 62 are indicated by the reference character 115 64. The arrangement of the belts 63, 64 is the same as that illustrated with respect to the belts 44, 45. By arranging the shafts 60 and 62 above the plane of the shafts 59 and 61, the belts 63, 64 are positioned at a downward inclination, so that the finished paper will be conveyed in a downward direction from the pair of presser rolls 23, 24, or, in other words, in an opposite direction to that of the feed of the paper. The 120 125 130

shafts 59, 60, 61, and 62 are journaled in protuberances 65 extending from each face of an upright 6 of a supporting frame of each pair of supporting frames. The shaft 59 is connected by a transmission belt 66 to the projecting end 67 of the shaft 25, upon which is mounted the roll 23.

Each of the supporting frames has extending therein a pair of manually operated screws 68 which are connected and vertically adjust the bearings 13 for holding the rolls 21, 23 down upon the rolls 22, 24, and, at the same time, maintaining the rolls 21, 23 under screw pressure. That supporting frame 15 which is adjustable upon the base enables, when the said frame is adjusted toward the other frame, the removal of the belts 37, 38 from the presser rolls when occasion so requires. The belts 37, 38 are always kept under tension owing to the contact therewith of the stretcher rolls 47, 48. These rolls are always adjusted to keep the belts 37, 38 taut if they ever become slack.

From the foregoing construction, it is evident that, when motion is imparted to the shaft 34, the belts 37 and 38 will be caused to travel in the same direction, and, owing to the operation of the shaft 25 which carries the roll 21, motion will be imparted to the shaft 42, which, in turn, will operate the belts 45, and, owing to the arrangement of the rolls 32, 41, 42, and 43 in close proximity, both series of belts 44, 45 will travel and feed the paper to be treated to between the belts 37, 38 at a point between the rolls 21, 22. Motion being imparted to the feeding device, the dust or wiper rolls 53, 54 will also be rotated, owing to the manner in which the shafts for said rolls are connected with the shafts 32, 42. When the belts 37, 38 travel, the shaft 25 will be rotated, which, in turn, will cause operation of the conveying device, owing to the manner in which the conveying device is connected with the said shaft 25.

Although it is stated that the machine operates upon paper blanks so as to impart to the surface of the blanks a cloth or satin finish, yet the paper can be fed to the machine from a continuous roll.

Having thus fully described our invention, what we claim as new and desire to secure by Letters Patent is:

1. A machine for cloth finishing the surface of paper comprising a pair of endless belts opposing one another and, between which the material to be treated is inserted, and an upper and a lower pair of rotatable presser rolls each having a smooth periphery associating with said belts and adapted to exert pressure through the belts upon the material.

2. A machine for cloth finishing the surface of paper comprising a pair of imperforate and smooth endless belts between which the material to be treated is inserted, each of

said belts having an inner resilient section, and an upper and a lower pair of rotatable presser rolls each having a smooth periphery associating with said belts for exerting pressure upon the material through the belts. 70

3. A machine for cloth finishing the surface of paper comprising a pair of endless belts between which the material to be treated is inserted, each of said belts consisting of an imperforate and smooth resilient inner section and an imperforate and smooth textile outer section, the textile section of one belt opposing the textile section of the other belt, and two pairs of presser rolls each having a smooth periphery, associating with said belts and adapted to exert pressure through the belts upon the material. 75

4. A machine for finishing the surface of paper comprising a pair of endless belts opposing one another and between which the material to be treated is inserted, an upper and a lower pair of rotatable presser rolls associating with said belts and adapted to exert pressure through the belts upon the material, means for feeding the material to the belts at an inclination, and means for conveying the finished material from the belts at an inclination. 80

5. A machine for finishing the surface of paper comprising a pair of endless belts between which the material to be treated is inserted, each of said belts having an inner resilient section, an upper and a lower pair of rotatable presser rolls associating with said belts for exerting pressure upon the material through the belts, means for feeding the material to the belts at an inclination, and means for conveying the finished material from the belts at an inclination. 85

6. A machine for finishing the surface of paper comprising a pair of endless belts between which the material to be treated is inserted, each of said belts consisting of a resilient inner section and a textile outer section, the textile section of one belt opposing the textile section of the other belt, two pairs of presser rolls associating with said belts and adapted to exert pressure through the belts upon the material, means for feeding the material to the belts at an inclination, and means for conveying the finished material from the belts at an inclination. 90

7. A machine for cloth finishing the surface of paper comprising a pair of endless belts opposing one another and between which the material to be treated is inserted, an upper and a lower pair of rotatable presser rolls each having a smooth periphery, associating with said belts and adapted to exert pressure through the belts upon the material, and stretcher roll associating with each of said belts. 95

8. A machine for cloth finishing the surface of paper comprising a pair of endless belts between which the material to be 100

treated is inserted, each of said belts having an inner resilient section, an upper and a lower pair of rotatable presser rolls each having a smooth periphery associating with said belts for exerting pressure upon the material through the belts, and a stretcher roll associating with each of said belts.

9. A machine for cloth finishing the surface of paper comprising a pair of endless belts between which the material to be treated is inserted, each of said belts consisting of an imperforate and smooth resilient inner section and an imperforate and smooth textile outer section fixedly secured to the other section, the textile section of one belt opposing the textile section of the other belt, two pairs of presser rolls each having a smooth periphery, associating with said belts and adapted to exert pressure through the belts upon the material, and a stretcher roll associating with each of said belts.

10. A machine for finishing the surface of paper comprising a pair of endless belts opposing one another and between which the material to be treated is inserted, an upper and a lower pair of rotatable presser rolls associating with said belts and adapted to exert pressure through the belts upon the material, and a wiper roll associating with each of said belts.

11. A machine for finishing the surface of paper comprising a pair of endless belts between which the material to be treated is inserted, each of said belts having an inner resilient section, an upper and a lower pair of rotatable presser rolls associating with said belts for exerting pressure upon the material through the belts, and a wiper roll associating with each of said belts.

12. A machine for finishing the surface of paper comprising a pair of endless belts between which the material to be treated is inserted, each of said belts consisting of a resilient inner section and a textile outer section, the textile section of one belt opposing the textile section of the other belt, two pairs of presser rolls associating with said belts and adapted to exert pressure through the belts upon the material, and a wiper roll associating with each of said belts.

13. A machine for cloth finishing the surface of paper comprising a pair of endless belts opposing one another and between which the material to be treated is inserted, an upper and a lower pair of rotatable presser rolls each having a smooth periphery, associating with said belts and adapted to exert pressure through the belts upon the material, and adjusting screws for one pair of presser rolls.

14. A machine for cloth finishing the surface of paper comprising a pair of endless belts between which the material to be treated is inserted, each of said belts having an

inner resilient section, an upper and a lower pair of rotatable presser rolls each having a smooth periphery, associating with said belts for exerting pressure upon the material through the belts, and adjusting screws for one pair of presser rolls.

15. A machine for cloth finishing the surface of paper comprising a pair of endless belts between which the material to be treated is inserted, each of said belts consisting of a resilient inner section and a textile outer section fixedly secured to the other section, the textile section of one belt opposing the textile section of the other belt, two pairs of presser rolls associating with said belts and adapted to exert pressure through the belts upon the material, and adjusting screws for one pair of presser rolls.

16. A machine for cloth finishing the surface of paper comprising a pair of endless belts opposing one another and between which the material to be treated is inserted, an upper and a lower pair of rotatable and smooth presser rolls associating with said belts and adapted to exert pressure through the belts upon the material, and adjustable means for keeping the belts taut.

17. A machine for cloth finishing the surface of paper comprising a pair of imperforate and smooth endless belts between which the material to be treated is inserted, each of said belts having an inner resilient section, an upper and a lower pair of rotatable presser rolls each having a smooth periphery, associating with said belts for exerting pressure upon the material through the belts, and adjustable means for keeping the belts taut.

18. A machine for finishing the surface of paper comprising a pair of endless belts between which the material to be treated is inserted, each of said belts consisting of a resilient inner section and a textile outer section, the textile section of one belt opposing the textile section of the other belt, two pairs of presser rolls associating with said belts and adapted to exert pressure through the belts upon the material, and adjustable means for keeping the belts taut.

19. A machine for cloth finishing the surface of paper comprising a pair of smooth and endless conveying elements between which the paper to be treated is inserted, a plurality of smooth pressure exerting devices for said elements, means for retaining said elements taut, material feeding devices arranged in operative relation with respect to such elements, and material discharging devices arranged in operative relation with respect to said elements.

20. A machine for cloth finishing the surface of paper comprising a pair of conveying elements between which the material to be treated is inserted and each of which com-

prises a textile outer section and a yielding inner section fixedly secured to the outer section, and a pressure exerting means for said elements.

5 21. A machine for cloth finishing the surface of paper comprising a pair of conveying elements between which the material to be treated is inserted and each of which comprises a textile outer section and a yielding inner section fixedly secured to the outer section, a pressure exerting means for said elements, and means for retaining said elements taut.

15 22. A paper finishing machine comprising a pair of conveying elements between which the material to be treated is inserted and each of which comprises a textile outer section and a yielding inner section, a pressure exerting means for said elements, and wiping devices for the outer section of each of said elements.

20 23. A machine for cloth finishing the surface of paper comprising a pair of smooth feeding elements between which the paper to be treated is inserted and each of which comprises a textile outer section and a yielding inner section fixedly secured to the other sec-

tion, and means for successively exerting pressure against such elements.

25 24. A machine for cloth finishing the surface of paper comprising a pair of smooth feeding elements between which the paper to be treated is inserted and each of which comprises a textile outer section and a yielding inner section fixedly secured to the other section, means for successively exerting pressure against such elements, and means for retaining said elements taut.

30 35 25. A paper finishing machine comprising a pair of feeding elements between which the paper to be treated is inserted and each of which comprises a textile outer section and a yielding inner section, means for successively exerting pressure against such elements, and wiping devices for the outer section of each of said elements.

In testimony whereof we have hereunto set our hand in presence of two subscribing witnesses.
